UNITED STATES PATENT OFFICE.

FRANK DANIELSON, OF CHICAGO, ILLINOIS.

VISE.

Application filed August 23, 1920. Serial No. 405,275.

To all whom it may concern:

Be it known that I, FRANK DANIELSON, a citizen of the United States, residing at Chicago, in the county of Cook and State of Illinois, have invented a certain new and useful Improvement in Vises, of which the following is a full, clear, concise, and exact description, reference being had to the accompanying drawings, forming a part of this specification.

This invention relates to vises and more particularly to a vise that is adapted for securely holding various automobile parts without any damage thereto, such for example as pistons, cam shaft bearings, bearing caps, reverse gears, etc.

It is a purpose of the invention to provide a vise that is particularly adapted for holding Ford cam shaft bearings so that the same will not be bent out of shape while reaming the same. It is also a purpose of the invention to provide suitable means for holding bearing caps tightly in position in said vise.

It is a further purpose of the invention to provide suitable means on a vise of this character to prevent a reverse gear from turning in said vise, said means comprising a suitable lug or pin on the rear of said vise adapted to engage certain portions of said reverse gear to hold the same, said lug or pin being movable into and out of operative position.

It is a further purpose of the invention to provide a suitable guide for filing valve stems in said vise. To accomplish this purpose the vise is provided with an operating cam having a hollow hardened pivot pin serving as a guide for this purpose. It is also an object of the invention to provide suitable means for clamping the valve in position in said hollow pin for filing.

Other objects and advantages of the invention will appear as the description of the accompanying drawings proceeds, in which—

Fig. 1 is a view partly in side elevation and partly in vertical section of the improved vise, partly broken away, showing a piston in position therein;

Fig. 2 is a top plan view of the device with the piston removed therefrom;

Fig. 3 is a vertical section of the im-

proved vise showing the same when arranged for reaming cam shaft bearings; 55

Fig. 4 is a top plan view of a cam shaft bearing clamping collar showing the cam shaft bearing in place therein;

Fig. 5 is a vertical sectional view of a portion of the vise showing the same arranged for holding a bearing cap; 60

Fig. 6 is a section taken on line 6—6 of Fig. 5; and

Fig. 7 is a vertical sectional view of a portion of the vise showing the same as holding a reverse gear, and showing means for holding the reverse gear from turning in operative position. 65

Referring in detail to the drawings the improved vise is mounted on any suitable table or base member 10, and comprises a base portion 11 which has formed integral therewith a fixed jaw member 12, which jaw member is provided with a substantially semi-circular inner face 13. Slidably mounted on the base 11 is a jaw member 14, said jaw member 14 also being provided with a curved inner face 15 that is substantially semi-circular. The jaw member 12 has outwardly extending end portions 16 in which are secured in any suitable manner the guide pins 17 and the jaw member 14 is provided with extensions 18 which are adapted to slidably receive the pins 17, which pins act as guides for the jaw member 14 as it is moved backward and forward on the upper face of the base 11. A cam member 19 provided with a flattened portion 19' is pivotally mounted on the upper face of the base portion 11 and is provided with a handle 20 for operating the same. It will be clear that when the cam 19 is in the position shown in Fig. 2 the jaws 12 and 14 will be forced toward each other to hold a member, such as the piston 21 shown in Fig. 1, therebetween. 70 80 85 90 95

In order to make it possible to use the vise for various size pistons, lining members or collars 22 are provided that fit on the interior of the jaws and are of such inner curvature as to properly fit the outer curved surface of the piston 21. The collar comprising the member 22 is provided with an inner facing of any suitable soft material, such as felt fibre or leather, to prevent marring of the piston. 100 105

In order to provide for the return of the jaws to an open position when the lever 20 is moved to a position at right angles to that shown in Fig. 2, coil springs 23 are provided on each of the pins 17, which coil springs may directly engage the projecting portions 16 and 18 on their opposed flat faces or plates, such as the plates 24 shown in Fig. 2, may be mounted between the ends of the coil springs and the flat faces of the portions 16 and 18. The plates 24 extend inwardly beyond the curved surfaces of the jaws 12 and 14 and engage the end portions of the members 22 so as to hold the same in engagement with the jaws 12 and 14. The pivot pin for the cam member 19 is made with a central bore 25 adapted to receive the stem 26 of a valve 27 and is hardened for a purpose that will be presently explained. The lower end portion of the bore 25 is provided with a flared mouth 25' so that the stem 26 may be more readily inserted therein. The upper end portion of the pivot pin 28 is provided with a flange 29 which bears on the upper surfaces of the cam 19 and the lower end of the pin extends through the enlargement 30 formed on the forward end of the base 11. The enlargement 30 is also provided with a suitable screw threaded opening to receive the set screw 31, which is provided with a suitable handle 32 for turning the same, and the pivot pin 28 is provided with an opening in alignment with the set screw 31. The set screw 31 serves the purpose of preventing the pin 28 from turning in the base 11 and also holds the pin 28 in place. The set screw 31 also serves the purpose of holding the valve stem 26 in any desired position within the hollow pin 28. The purpose of providing the hollow pin is to provide a guide for filing the end of the valve stem 26 off square as the pin 28 and flange 29 are hardened. All that is necessary in order to file off the end of the valve stem is to set the pin 28 in the desired position with the set screw 31 and then file off the projecting portion thereof until the same is flush with the upper surface of the flange 29, after which it will be impossible to file further as the flange 29 is hardened. The rear portion of the vise is provided with a boss or projection 33, which is provided with a horizontal bore 34 and a vertical bore 35. Within the latter bore is mounted to slide vertically a pin 36 provided with a pair of circumferential grooves 37 and 38, and mounted within the horizontal bore 34 is a coil spring 39 and a ball bearing 40, the ball being adapted to be pressed into either the grooves 37 or 38 by the pressure of the spring 39 thereagainst. It is, of course, understood that the opening 34 is closed at the outer end by means of a suitable plug 41. The strength of the spring 39 is such that the pin will be held in either the position

shown in Fig. 1 or that shown in Fig. 7 by the pressure of the spring against the ball 40, but if the operator pulls on the pin 36 he may raise it from the position shown in Fig. 1 to that shown in Fig. 7 as the upward pull will unseat the ball from the curved groove 37 and will compress the spring, and the ball 40 will then seat in the groove 38 when the same comes in alignment therewith. Similarly by a downward pressure on the pin 36 it can be forced from the position shown in Fig. 7 to that shown in Fig. 1. The pin 36 is used as shown in Fig. 7 in which there is shown a reverse gear 42 suitably mounted between the jaws 14 and 12, a split ring 43 being interposed between the jaws of the vise and the pinion 44 on the reverse gear to hold the same firmly within the jaws of the vise. If nothing were provided to prevent the reverse gear from turning in the vise, the reverse gear would turn in the collar or split ring 44 when operated on by a reamer or similar tool.

In order to prevent the turning thereof the pin 36 is raised to the position shown in Fig. 7, when the pin will engage in one of the openings 45 between the spokes formed in the web portions 46 of the member 47 of the reverse gear, thus holding the same from turning. When the vise is used for other purposes, the pin 36 is moved to the positions shown in Figs. 1 and 3.

In Figs. 3 and 4 the vise is shown clamping a cam shaft bearing 48, such as is used in a Ford automobile. The cam shaft bearing 48 is made in one piece as will be clear from Fig. 4, and is provided with V-shaped grooves 49 that extend nearly entirely through the material of the bearing at diametrically opposite points. It will be evident that if such a bearing as that shown were placed in an ordinary vise the same would be very easily bent out of shape due to the weakened portions at 49. The purpose for providing the weakened portions at 49 is to make it possible to separate the two halves of the bearings as they would be when put in use by a blow of a hammer. However, it is usually necessary to ream out the inside of the bearings before putting the same in place, as these are made a trifle small in the factory.

In order to do this reaming it is necessary to provide means for clamping the bearing without distorting the same.

In Figs. 3 and 4 the bearing 48 is shown as being provided with suitable means for holding the same, and in Fig. 3 the reamer 50 is shown in position therein. The holding means for the bearing comprises a collar 51 made up of the two portions 51 and 52, which collar is provided with a bore in the upper portion thereof large enough to receive the bearing 48, and at the lower end thereof with a smaller bore 53 large enough

for the reamer 50 to pass therethrough and a ledge 54 is provided upon which the bearing 48 is adapted to rest. The lower end portion 55 of the collar is made small enough to 5 pass through the opening 56 in the face so that the offset portion 57 may rest suitably upon the upper surface of the base member 11. The upper portion of the collar 51 is provided with a circumferential groove 58 10 within which the split ring 59 is adapted to lie. The ring 59 is made of resilient material, and is adapted to hold the members 52 and 51 in assembled relation, but permits the same to be spread enough to receive the bearing 48. The collar comprising the members 51 and 52 is suitably mounted between the jaws of the vise and suitable bushings or lining members 22' are interposed between the jaws 14 and 12 and the members 51 15 and 52 so that the same will properly fit within the jaws of the vise.

In Figs. 5 and 6 the vise is shown as being used for holding the bearing cap 60 in position while filing the same, the file being 25 shown at 61. The devices for holding the bearing cap 60 comprise a pair of members 62 and 63 which together form a block having a circular outer face adapted to fit within the bushing or ring portions 22'', which 30 have an external curvature fitting that of the external curvature of the jaws 10 and 14. The members 62 and 63 are the halves of a block which together form a central recess 64 which is adapted to receive the upwardly 35 curved portions 65 of the bearing cap 60, the recess 64 being provided with laterally extending portions 66. The block portions 62 and 63 are each provided with a vertical bore adapted to receive one of the legs 67 40 of the U-shaped resilient member 68, the resilient member being adapted to hold the two halves of the block in assembled relation, and the extreme end portions 69 thereof extend upwardly beyond the upper flat faces 45 of the blocks 62 and 63 to be received within the bolt openings 70 in the bearing cap 60 to hold the same firmly in position upon the blocks 62 and 63 while filing the same as shown in Fig. 5. As the members 62 and 50 55 63 forming the block are securely clamped within the vise, and as the portions 69 hold the member 60 firmly in position, and as the portion 65 of the member 60 is firmly seated within the hollow portion 64 the bearing cap will not slip as the file 61 is operated over the surface thereof.

Having thus described my invention I desire to have it distinctly understood that I do not intend to limit myself to the exact details of structure shown in the accompanying drawings and described in the foregoing specification, except as defined by the following claims:

1. A vise of the character described comprising a base, a pair of clamping jaws on

said base, one of said jaws being movable relatively to said base, a hollow pivot pin mounted on said base and a cam for moving said jaw member on said pivot pin, said pivot pin having a hardened top surface 70 whereby the same is adapted to serve as a guide for filing valve stems.

2. A vise of the character described comprising a base, a pair of jaws on said base, one of said jaws being movable relatively to 75 said base, a pivot pin provided with a longitudinal bore mounted on said base, and a cam for moving said jaw mounted on said pivot pin, said pivot pin being adapted to receive a valve stem therein and having a hardened 80 top surface whereby the same serves as a guide for filing the same.

3. A vise of the character described comprising a base, a pair of jaws on said base, one of said jaws being movable relatively 85 to said base, a pivot pin provided with a longitudinal bore mounted on said base, and a member for moving said jaw mounted on said pivot pin, said pivot pin having a hardened flat top face adapted to serve as a guide 90 for filing valve stems.

4. A vise of the character described comprising a base, a pair of jaws on said base, one of said jaws being movable relatively to 95 said base, a hardened pivot pin provided with a longitudinal bore mounted on said base, and a member for moving said jaw mounted on said pivot pin, said pivot pin being adapted to receive a valve stem within 100 said bore and having a flange at the upper end thereof to provide a flat top face to serve as a guide for filing a valve stem.

5. A vise of the character described comprising a base, a pair of semi-circular clamping jaws on said base, one of said jaws being 105 movable relatively to said base and the other being fixed, means for moving said movable jaw toward and away from said fixed jaw, and a pin mounted in one of said jaws said pin being adapted to be projected upwardly, 110 said jaws and said pin cooperating to hold a reverse gear against turning when said pin is in projected position.

6. A vise of the character described comprising a base, a pair of semi-circular clamping jaws on said base, one of said jaws being 115 movable relatively to said base and the other being fixed, means for moving said movable jaw toward and away from said fixed jaw, and a pin mounted for vertical sliding movement in one of said jaws adapted to project upwardly therefrom, said jaws and said pin cooperating to hold a reverse gear against turning.

7. A vise of the character described comprising a base, a pair of semi-circular clamping jaws on said base, one of said jaws being 125 movable relatively to said base and the other being fixed, means for moving said movable jaw toward and away from said fixed jaw, a 130

pin mounted for vertical sliding movement, in one of said jaws and adapted to project upwardly therefrom or be retracted substantially flush with the top surface of said jaw, and spring means for holding said pin in either its projected or retracted position.

8. In a device of the character described, a base member, a hardened tubular member mounted therein, said member having a flange at the upper end thereof serving as a guide for filing valve stems, and means for clamping a valve stem within the bore of said tubular member.

9. In a device of the character described, a base member, a hardened tubular member mounted therein, said member having a flange at the upper end thereof serving as a guide for filing valve stems, and a member having screwthreaded engagement with said base member for clamping a valve stem within the bore of said tubular member.

10. A vise of the character described comprising a base, a pair of semi-circular jaw members, one of said jaw members being fixed on said base and the other of said jaw members being movable on said base, guides for said movable jaw member on said fixed jaw member, resilient means mounted on said guides, a pair of substantially semi-circular members mounted in said jaws and bearing plates slidably mounted on said guides, said resilient means urging said plates away from each other.

11. A vise of the character described comprising a base, a pair of semi-circular jaw members, one of said jaw members being fixed on said base and the other of said jaw members being movable on said base and being provided with openings adapted to receive guide pins on said fixed jaw member, springs mounted on said guide pins, a pair of substantially semi-circular members mounted in said semi-circular jaws, and plates slidably mounted on said guide pins, said plates being urged against the end por-

tions of said semi-circular members by said springs to hold said members in position in said jaws.

12. A vise of the character described comprising a base, a pair of semi-circular jaw members, a split block with a curved outer face adapted to fit between said jaw members and be clamped therebetween and having a socket portion adapted to receive the outer curved surface of a bearing cap therein, said block comprising a pair of similar members, and a U-shaped resilient pin for holding said members in abutting relation.

13. A vise of the character described comprising a base, a pair of semi-circular jaw members, a split block with a curved outer face adapted to fit between said jaw members and be clamped therebetween, and having a socket portion adapted to receive the outer curved surface of a bearing cap therein, said block comprising a pair of similar members, and a U-shaped resilient pin for holding said members in abutting relation, said U-shaped member extending beyond the upper face of said block and adapted to be received in the bolt openings of said bearing cap to hold said bearing cap in position on said block.

14. A vise of the character described comprising a base, a pair of jaws on said base, one of said jaws being movable relatively to said base, a hardened pivot pin provided with a longitudinal bore mounted on said base, a member for moving said jaw mounted on said pivot pin, said pivot pin having a flange at the upper end thereof, and means mounted in said base engaging said pivot pin to hold the same against upward movement, said means extending into the bore of said pivot pin whereby the same is adapted to clamp a member in position thereon.

In witness whereof, I hereunto subscribe my name this 31st day of July, A. D., 1920.

FRANK DANIELSON.
